UNITED STATES PATENT OFFICE

JULIAN MAAS, OF ST. LOUIS, MISSOURI

DESIGN FOR A MILLINERY DISPLAY FIXTURE

Application filed January 23, 1933. Serial No. 46,945. Term of patent 7 years.

To all whom it may concern:

Be it known that I, JULIAN MAAS, a citizen of the United States, residing at St. Louis, Missouri, have invented a certain new, original, and ornamental Design for a Millinery Display Fixture, of which the following is a specification, reference being made to the accompanying drawing, forming a part

thereof, in which Figure 1 is a front slightly perspective view and Figure 2 is a side elevational view of a millinery display fixture embodying my design.

I claim—

The ornamental design for a millinery display fixture, substantially as shown.

JULIAN MAAS.
